DESIGN FOR MOBILE CART

John P. Salsgiver, West Acton, Mass., assignor to United Technical Corporation, West Concord, Mass.

Filed Nov. 22, 1971, Ser. No. 201,249

Term of patent 14 years

Int. Cl. D12—02; D6—04
U.S. Cl. D12—27

FIG. 1

FIG. 2

FIG. 3

FIG. 1 is a perspective view of a mobile cart showing my new design;

FIG. 2 is a front elevational view; and

FIG. 3 is a right side elevational view.

The rear of the cart, not shown in the drawing is substantially plain and unornamented.

I claim:

The ornamental design for mobile cart, as shown and described.
